INVENTOR.

James Jenkinson,

BY Francis C. Bowen

ATTORNEY,

UNITED STATES PATENT OFFICE.

JAMES JENKINSON, OF BROOKLYN, NEW YORK.

CLASP.

SPECIFICATION forming part of Letters Patent No. 377,429, dated February 7, 1888.

Application filed October 27, 1887. Serial No. 253,526. (No model.)

To all whom it may concern:

Be it known that I, JAMES JENKINSON, a citizen of the United States, and a resident of Brooklyn, in the county of Kings and State of New York, have invented certain new and useful Improvements in Clasps, of which the following is a specification.

My invention relates to a clasp for securing the elastic webbing to steels for use as stays in ladies' dresses and for other purposes; and it consists of the novel features, hereinafter described, whereby I obtain an article of superior strength and effectiveness and one of easy application to use.

In the accompanying drawings, Figure 1 is the plan view of the blank used in the manufacture of my skirt-stay. Fig. 2 is a sectional view thereof when folded. Fig. 3 is a front view of the clasp applied to the stay and webbing for use. Fig. 4 is a view of an end of the stay. Fig. 5 is a longitudinal central section of the clasp, stay, and webbing united. Fig. 6 is a back view of the clasp applied to the stay and webbing for use, being opposite of Fig. 3. Figs. 7, 8, and 9 are views of my invention with the lips omitted.

Similar letters of reference indicate corresponding parts.

The letter A designates a blank composed of sheet metal, which is substantially cross-shaped, having the head a on the top and the arms b b projecting from the sides thereof, while the center is provided with an opening, d, having the lips e e on each side thereof to receive the edges of the webbing and secure it to the steel at the portions s s s, while the body of the webbing is held by the portions i i of the clasp, which extend entirely across the elastic webbing and press it on the steel.

By providing the clasp with the lips e e, the webbing can be more easily threaded or passed through the clasp over the lips, so that the edges of the webbing will be positively held between the edges of the lips, even when the clasp is not on the stay, and the upper and lower transverse portions of the clasp, as shown at s s, Figs. 5 and 6, while the head portion of the clasp-blank also affords an additional holding service for the webbing and provides another safeguard against the webbing breaking loose from the steel, as shown in Figs. 1, 3, 5, and 8. In some instances the lips e e may be dispensed with, as shown in Figs. 7 and 9.

In combination with my clasp I prefer to use a stay provided at each end with an opening, forming a fork, P, which has the advantage of being easily and economically made, and, moreover, permits the rubber to be sewed through said opening P and the opening d in the clasp to the dress fabric, which effectually prevents the steel from displacement while in use, as it secures the rubber to the dress, and holds it to the dress in case the webbing in the clasp should give way, as would be the case in the event eyelets were used to secure the webbing to the steel. When two steels are used side by side, the clasp may be arranged over the ends thereof, in which case the opening P in the steels may be omitted.

In applying the clasp to use the webbing is drawn through under the lips e e, so as to lie upon the flat portions i i of the blank. The steel is then laid upon said lips from an opposite direction to the webbing and the blank is folded upon itself on both side edges until the arms b b meet, as shown in Figs. 3 and 7, and by this means the tips i i are forced down upon the webbing, thereby firmly holding it in position, and at the same time exerting an outward pressure upon the steel, with a tendency to bind it between themselves and said folded edges of the clasp.

What I claim as new, and desire to secure by Letters Patent, is—

1. The clasp herein described for securing the webbing and steels together for use as stays in ladies' garments, formed of a single piece of sheet metal, and with a central opening having lips on the sides thereof for holding the edges of the webbing, and transverse portions at the ends for holding the body of the webbing to the stays, as herein shown and described.

2. The clasp herein described for securing the webbing and steels together for use in ladies' garments, formed of a single piece of sheet metal provided with a central opening and side lips, in combination with a steel having forked openings, substantially as shown and described.

JAMES JENKINSON.
